UNITED STATES PATENT OFFICE.

SAMUEL M. KITCHEN, OF SALEM, NEW YORK, ASSIGNOR TO BARTLETT ALL STEEL SCYTHE COMPANY, INC., A CORPORATION OF NEW YORK.

SCYTHE.

1,278,938.

Specification of Letters Patent. Patented Sept. 17, 1918.

Application filed April 19, 1917. Serial No. 163,135.

To all whom it may concern:

Be it known that I, SAMUEL M. KITCHEN, a subject of the King of Great Britain, residing at Salem, in the county of Washington and State of New York, have invented certain new and useful Improvements in Scythes, of which the following is a specification.

This invention relates to improvements 10 in scythes, and the invention relates particularly to the construction of the heel-end of the scythe blade and the tang.

The object of the invention is to provide a relatively thin high grade tool steel scythe 15 blade, preferably made out of sheet steel which requires a minimum of forging to reduce it to proper shape and consistency. A further object is to provide novel and simple means for reinforcing the heel-end of the 20 blade and also the tang, by increasing the thickness of the metal in these parts at the points where the greatest strains are experienced, and to accomplish this object without the use of rivets or of folding and rolling the said parts. And a further object is 25 to corrugate certain portions of the heel end of the blade in a novel manner for increasing the strength and for preventing the buckling of the blade.

30 A further object is to improve the devices shown in my United States Patent No. 1,187,482, dated June 13, 1916, and also my pending application Serial No. 115,532.

I attain these objects by the means set 35 forth in the detailed description which follows, and as illustrated by the accompanying drawing, in which—

Figure 1 is a broken plan view; showing the sheet metal blank from which my im- 40 proved blade is made.

Fig. 2 is a plan view of the blank comprising the sheet metal reinforcing member.

Fig. 3 is a broken plan view of the heel-end of the blade after the reinforcing mem- 45 ber has been permanently welded to the blade proper, and the whole operated upon for producing the finished article.

Fig. 4 is a transverse section taken on line 4—4 of Fig. 3.

50 Fig. 5 is a similar view taken on line 5—5 of Fig. 3.

Fig. 6 is a longitudinal section taken on line 6—6 of Fig. 3.

In the drawing, 2 represents the blank 55 from which the blade is made, which consists

of a plane sheet of tool steel for producing a keen and lasting cutting edge when properly tempered. The blank 2 is preferably normally of the proper gage and therefore does not require any rolling or forging for 60 bringing it to the proper thickness. 3 represents the cutting edge of the blade, and 4 represents the back flange portion, which in the finished article is bent upwardly substantially at right angles to the body of the 65 blade (see Figs. 3, 4, and 5). The broad heel-end 5 tapers upwardly toward the back flange 4, for providing a relatively narrow neck 6 to which is integrally joined a tang 7. The blank 2 of Fig. 1 is preferably of the 70 same gage throughout, and the back flange 4 preferably extends partially across the rounded end of the tang for stiffening the neck 6.

It is known that a scythe blade is weakest 75 at its heel-end, which includes the portions 5 and 6, and a particular object of the present invention is to suitably reinforce said parts so as to give to the whole blade the requisite strength and stiffness. The reinforcement referred to consists of overlaying a portion of the heel-end 5, as well as the neck 6, and the tang 7, with a sheet metal plate or part 8, which is first blanked-out 80 of sheet steel, as shown in Fig. 2, having an angular web 8', and a tang 8'', corresponding to the similar parts of the blade 2. The plate 8 may consist of any suitable grade of steel. The blank 8 is disposed upon the blank 2 (see dotted lines in Fig. 3), where 85 it is temporarily held in place preferably by "spot" welding. The heel-end of the blades 2 with the overlaid portion 8 is next heated and then placed between suitable dies or forging tools and subjected to a sufficient pressure to firmly weld parts 8 and 2 together, as shown in Figs. 3, 4, 5 and 6. The dies (not shown) are preferably provided with 90 grooves and tongues, which during the welding operation referred to, mold or form two 95 or more ribs 9 and 10 on the top side of the blade, and corresponding grooves 9' and 10' in the bottom side of the blade. The rib 9 preferably extends from the neck 6 forwardly 100 toward the point of the blade substantially parallel to the back flange 4, while the rib 10 extends from a point substantially midway between the rib 9 and the cutting edge 3, at an angle of approximately 45°, to 105 and intersecting the rib 9 near its forward 110

end. The ribs 9 and 10 preferably taper, their broadest ends facing the tang 7. By this novel construction and arrangement of the heel-end of the blade, said end is doubled 5 in thickness. The rib 9 prevents the blade from bending or buckling at its narrowest point—neck 6, while the rib 10 prevents the broad heel portion 5 from twisting independently from the neck and tang. Thus 10 the weakest portions of the blade are adequately strengthened and stiffened. The ribs 9 and 10 are preferably positioned so that their outer edges 11 correspond to the margins 12 of the plate 8. By this provision, the laps or joints between the blades 2 and 8 are obscured. The back flange 4 may be bent up by means of the same dies employed for forming the ribs and grooves 9 and 10 at a single operation, if desired. 15 20 In any event, the main portion of the blade 2 beyond the reinforcing portions needs but one heating, therefore the high grade of the steel is not liable to be impaired. This latter feature is important for the reason that 25 under the old methods of constructing scythes, the blades were heated so many times that they were rendered soft and incapable of retaining sharp cutting edges for any length of time.

30 My method and means for reinforcing the heel-end of the scythe blade are extremely simple, and they are believed to be novel. The cost of construction as well as the labor

are greatly reduced, while the strength, durability and efficiency of the whole scythe is 35 materially improved.

Having thus described my invention what I claim as new and desire to secure by Letters Patent, is—

1. A scythe, including a blade of uniform 40 thickness throughout and having an integral tang separated from the blade by a neck, a reinforcing plate welded to the top face of the tang, the neck and a portion of the heel-end of the blade, and tapering reinforcing 45 ribs and grooves formed in the welded parts of the neck and heel-end of the blade, the said ribs and grooves converging and intersecting toward the pointed end of the blade.

2. A scythe, including a blade of uniform 50 thickness throughout and having an integral tang separated from the body of the blade by a neck, a reinforcing plate mounted upon and welded to the tang, the neck and a portion of the heel-end of the blade adjacent the 55 neck, a pair of ribs and grooves made from the welded parts, one of said ribs and its corresponding groove extending across the neck and a portion of the heel-end of the blade, the other rib and corresponding 60 groove extending obliquely from the rear-end of the blade and intersecting said first rib and groove toward the pointed end of the blade.

In testimony whereof I affix my signature. 65
SAMUEL M. KITCHEN.
